(57) **CLAIM**

The ornamental design for a razor blade sharpening device, as shown and described.

DESCRIPTION

This application is related to Pat. No. 7,275,461 issued to applicant.

FIG. 1 is a top, rear, and right side perspective view of a razor blade sharpening device showing my new design,

FIG. 2 is an additional top, rear, and right side perspective view thereof;

FIG. 3 is a front elevational view thereof;

FIG. 4 is a side elevational view thereof, the side opposite being a mirror image of that shown;

FIG. 5 is a top plan view thereof;

FIG. 6 is a top, front, and right side perspective view thereof;

FIG. 7 is an additional top plan view thereof; and,

FIG. 8 is an additional side elevational view thereof.

The broken-line disclosure of a hand held razor in the views is for illustrative purposes only and forms no part of the claimed design, and the broken-line structure within the device is a portion of the article in which the claimed design is embodied, but which forms no part of the claimed design.
